UNITED STATES PATENT OFFICE

2,510,353

RAILWAY TRUCK BOLSTER SUSPENSION

James C. Travilla, Jr., University City, Mo., assignor to General Steel Castings Corporation, Granite City, Ill., a corporation of Delaware

Application April 24, 1948, Serial No. 22,990

6 Claims. (Cl. 105—190)

1

The invention relates to railway rolling stock and more particularly to railway trucks of the type described in Patent No. 2,163,253, issued June 20, 1939, to Emil C. Anderson, and in which the load-supporting bolster is carried by springs mounted on a multiple part spring plank suspended by swing hangers from the truck frame.

The several parts of the multiple part spring plank as used heretofore are separated by rollers which roll on concaved seats on each of the parts and provide for relative lateral movement of the parts due to lateral shocks induced by rail joints and other track irregularities, variations in wear of the wheel tread and draft and buffing forces. Relative movement of the spring plank parts is not adequately damped or cushioned to provide a smooth riding truck at the high speeds at which railway vehicles are operated today. The parts, after movement relative to one another from their normally centered position by a lateral force, upon their release from the force, move to and fro relative to one another and past their normally centered position.

One object of the invention is to adequately cushion or damp the movement of the spring plank parts to reduce the tendency of the spring plank parts to move past their normally centered position after their release from a lateral force.

Another object is to reduce wear of the spring plank parts to a minimum.

Another object is to simplify construction of the truck yet provide, in a two-part spring plank truck, substantially the same flexibility and riding qualities as in a conventional triple bolster truck.

Other objects will be apparent to those skilled in the art from the following description and accompanying drawings, in which:

Figure 1 is a top view of a longitudinal half of the center portion of a railway truck constructed according to the invention, a portion being sectioned horizontally on the line 1—1 of Figure 2.

Figure 2 is in part a side view and in part a longitudinal vertical section taken approximately on the line 2—2 of Figure 1.

Figure 3 is a transverse vertical section taken approximately on the line 3—3 of Figure 2 and drawn to enlarged scale and showing the spring plank parts in their normal positions.

Figure 4 is a view similar to Figure 3 drawn to enlarged scale and showing the spring plank parts displaced laterally relative to one another.

Figure 5 is a bottom view of the upper spring plank part and the adjacent truck parts, with

the supporting pads applied to the spring plank. The truck includes the usual wheels 1, axles 2 and journal boxes 3. Equalizers 4 are mounted on boxes 3 and mount truck springs 5 which carry a truck frame 6. The truck is of the lateral motion bolster type and has pairs of swing hangers 7 at opposite sides of the truck pivotally suspended from frame 6 by pins 8. Each pair of hangers 7 carries a cross bar 9.

10 A two-part spring plank 10 has a lower part 11 and an upper part 12 extending transversely from side to side of the truck. Lower part 11 is supported at its ends by cross bars 9 and upper part 12 seats a pair of coil springs 13 at each of its ends. Springs 13 carry a bolster 14 having a center plate 15 for mounting a car body (not shown).

20 A vertically disposed shock absorber 22 at each side of the truck is connected at one end to a bracket 23 on the truck frame and at the other end to a bracket 24 on an extension 27 on bolster 14 and controls vertical movement of the bolster relative to truck frame 6. A horizontally disposed tie bar 25 at each side of the truck is connected at one end to a bracket 26 on the truck frame and at the other end to extension 27 on the bolster and controls movement of the bolster longitudinally of the truck.

25 A yieldable pad 16 is seated on lower spring plank part 11 directly below each spring 13 and pads 16 mount upper spring plank part 12. Each pad 16 comprises alternate layers of steel 20 and rubber 21 bonded together.

Opposing faces of spring plank parts 11 and 12 have seats for the pads to hold them in definite spaced relation. The seats on lower spring plank part 11 include upstanding ribs 17 of substantially uniform height surrounding the pads. The seats on upper spring plank part 12 include depending ribs 18 extending transversely of the bolster and ribs 18c and 18d positioned at the inner and outer sides of the pads. Each rib 18 projects downwardly as indicated at 18a and curves away from the adjacent pads as indicated at 18b. Members 18c near the sides of the spring plank extend downwardly farther than members 18d which are near the center line of the spring plank.

30 The pads distort in shear when forces are exerted on upper and lower spring plank parts 11, 12 in opposite directions, laterally of the truck, thus providing for limited relative movement of parts 11, 12 transversely of the truck.

35 As the pad distorts in shear its successive plates 20b, 20c, 20d, and 20e move successively increas-

ing distances from the top downwardly. If the opposing faces 18b were straight, the edges of all these plates would eventually engage the face simultaneously and the pad's resistance to shear would increase uniformly with each unit of relative lateral movement of parts 11, 12 until this engagement occurred, but since face 18b is curved, the edges of successive plates engage the face at intervals. As successive plates contact the surface, the effective height of the pad gradually decreases and the resistance of the pad to distortion in shear gradually increases. Hence, the resistance of the pad to relative lateral movement of the spring plank parts 11, 12 increases at a rate greater than the rate of increase of relative lateral movement of parts 11, 12.

In Figure 4 lower spring plank part 11 has been moved to the left of its normal position relative to upper spring plank part 12 and without any swinging movement of hangers 7. Plates 20a, 20b, and 20c of pad 16 engage the inner curved portion of rib 18. Plates 20d, 20e, 20f, and 20g are spaced from rib 18 and the effective height of pad 16 is now that portion between plates 20c and 20g. When plates 20d and 20e engage rib 18, the effective height of the pad will decrease to that portion between plates 20e and 20g. Plates 20f and 20g lie below the lower edge of rib 18 and lateral movement of these plates is limited only by the resistance to distortion in shear of the rubber layers 21 bonded to these plates.

The resistance of pads 16 in shear for a certain amount of distortion, such as illustrated, is less than the force required to overcome the static friction between swing hangers 7 and their pins 8 and between cross bars 9 and the spring plank that is, it is less than the force necessary to cause pivotal movement of swing hangers 7. Hence, pads 16 absorb those transverse shocks of insufficient force to move hangers 7 on their pivots. In addition, they damp shocks of larger magnitude sufficient to cause lateral swinging action of the swing hangers, thereby preventing or reducing swaying and lurching of the car body. The swinging action of the swing hangers also tends to produce increasing resistance to the movement of truck frame 6 relative to bolster 14.

Internal friction in pads 16 distorting in shear dissipates the shock forces and cushions or damps movement of one spring plank part relative to the other, thus improving the riding qualities of the car. The details of construction may be varied substantially without departing from the spirit of the invention and the exclusive use of those modifications coming within the scope of the claims is contemplated.

What is claimed is:

1. In a railway vehicle truck, a frame, hangers pivotally suspended from said frame to swing transversely of the truck, a plank and a bolster extending transversely of the truck, said plank comprising a lower part extending from side to side of the truck and carried by said hangers, an upper part extending from side to side of the truck and supporting said bolster, and pad structure of rubber-like material between said upper part and said lower part and providing for limited relative movement of said parts transversely of the truck but resisting such movement at an increasing rate as the movement increases.

2. In a railway vehicle truck, a frame, hangers pivotally suspended from said frame to swing transversely of the truck, a spring plank, a bolster and bolster supporting springs, said spring plank

comprising a lower part extending from side to side of the truck and carried by said hangers, an upper part extending from side to side of the truck and mounting said bolster supporting springs, and a pad of rubber-like material between said upper part and said lower part, said pad being constructed and arranged to distort in shear laterally of the truck to accommodate at least a portion of the relative movement of the bolster and truck frame transversely of the truck independently of the swing hanger movement, the rate of resistance of the pad to lateral distortion increasing throughout the relative lateral movement of the two spring plank parts.

3. In a railway vehicle truck, a truck frame, swing hangers pivotally suspended therefrom, a lower spring plank part supported by said swing hangers, a pad of rubber-like material mounted on said lower part, an upstanding rib on said lower part defining a seat for said pad, an upper spring plank part mounted on said pad, and a downwardly extending rib on said upper part defining a seat for said pad, the rib on one of said parts projecting a substantial distance toward the other part and having a face adjacent said pad inclined away from said pad to provide for distortion of said pad in shear between its seated portions and for limited relative movement of said parts transversely of the truck when transverse lateral forces are applied to one of said parts, distortion of said pad in shear being limited by its engagement with said projecting rib.

4. Structure as described in claim 3 in which the projecting rib is contoured to progressively engage portions of the pad as the pad distorts in shear so that the resistance of the pad to lateral distortion increases at a rate greater than the rate of increase of lateral deflection.

5. Structure as described in claim 3 in which the projecting rib face adjacent the pad is curved downwardly and outwardly away from the pad.

6. A railway vehicle truck spring plank comprising a lower part adapted to extend from side to side of the truck, a pad of rubber-like material mounted near each end of said lower part, upstanding ribs near the ends of said lower part defining seats for said pads, an upper part extending between and supported on said pads with downwardly extending ribs defining seats for said pads, the ribs on one of said parts projecting a substantial distance toward the other part and having faces adjacent said pads inclined away from said pads to provide for limited distortion of said pads in shear between its seated portions.

JAMES C. TRAVILLA, JR.
